United States Patent Office.

ERNEST W. GILLES AND JULES WENDELL, OF OSWEGO, NEW YORK.

Letters Patent No. 85,924, dated January 19, 1869.

IMPROVED SCHOOL-DESK.

The Schedule referred to in these Letters Patent and making part of the same.

To all to whom it may concern:

Be it known that we, ERNEST W. GILLES and JULES WENDELL, of the city and county of Oswego, in the State of New York, have invented a new and improved Desk for Schools; and we do hereby declare that the following is a full and exact description thereof, reference being had to the accompanying drawing, and to the letters of reference marked thereon.

The nature of our invention consists in providing a hinge, adapted to a shoulder, occupying but little space, made easily adjustable by the hand, so that the teacher, pupil, or any person, can easily and readily let down the table-leaf and raise and fasten the same again.

This table-leaf, or top part of the desk, is so constructed, by means of this hinge, as to drop, and be raised horizontally, being held by part A, which is an arm of cast-iron, to which the table is made fast and secure, and this arm is represented on the diagram in Figure 1.

This arm is connected with an upright of iron, and at a short distance from its upper extremity, it is made fast by a pivot or bolt, and is held by part B, which is represented on the drawing in Figure 3, corresponding to the representation in Figure 2, which presents the side view.

By our improvement, we can, without difficulty or delay, place the table and the seat perpendicular, either together or separately, as may be desirable.

Attached to the cast-iron arm A, in fig. 1, and made a part of it, is the upper part of the hinge, which is held to the upright casting, at B, on fig. 1, by a pivot, movable at pleasure.

Connected with this arm, and made into a hinge by the use of a pivot, is a circular-slotted link, lettered C, made so as to pass freely and easily over another pivot, D, at its lower extremity, where there is a shoulder, on which it rests when the table is up, holding it firm and fast.

By raising the table slightly, and displacing from the pivot D the lower end of this circular-slotted link, the table can be let down perpendicular, and when raised, it fastens itself.

What we claim as our invention, and desire to secure by Letters Patent, is—

The combination of the arm A with slotted link C and standard B and its connections, by means of which the table is let down perpendicular, and when raised up, is held fast and secure, substantially as specified.

ERNEST W. GILLES.
JULES WENDELL.
